UNITED STATES PATENT OFFICE.

EMIL JOHN ENS, OF NEWARK, NEW JERSEY, ASSIGNOR TO ELLIS ADDING TYPE-
WRITER COMPANY, OF NEWARK, NEW JERSEY, A CORPORATION OF NEW JERSEY.

SELECTIVE MULTIPLE TABULATING STOP.

Application filed September 13, 1926. Serial No. 135,147.

This invention relates to a selective multiple tabulating stop adapted for use on the carriage of a printing tabulating and calculating machine, or, on the carriage of any 5 tabulating typewriter or combined typewriter and calculating machine.

While my invention is particularly intended for use on the well-known "Ellis" adding or bookkeeping machine, the invention is adapted for use on other machines and it is to be understood that the claims are not restricted to the use of the invention on any particular machine.

Instances of the use of a tabulating bar, 5 settable stops, and tabulating keys for use in connection with the "Ellis" machine are shown in the Ellis Patents Nos. 1,197,276 and 1,197,278.

Heretofore in the Ellis machine it has 0 been proposed to provide stops which may be independently set on the tabulating bar to provide for the tabulations required by the work being done. There are certain classes of work, however, wherein tabulation is required, in which the tabulations will recur 5 repeatedly in certain columns and in which the columns on successive sheets will bear the same relation to each other as to distance over and over again.

To meet the requirements of work of this character, I have provided a multiple selective tabular stop wherein the respective settable stops are combined in a unitary device which may be applied to the tabulating bar at any point of the length thereof and moved from place to place as a unit, or entirely removed from the bar and used independently of, or in conjunction with, the ordinary independent settable right and left marginal stops, or other stops which have heretofore been in use on the Ellis machine, or which may be desired be used according to the nature of the work to be done.

My improvements provide, in a unitary form, a plurality of settable stops one, or more, of which may be set and which have a common latch whereby any stop which may be depressed or set will be automatically latched, and any stop which is in set position will be automatically released and restored when another of said stops is set, unless a plurality of the stops be simultaneously set, whereupon the stops which are set will all be latched.

My improved selective multiple tabulating

stop provides a means whereby printing may be had in all columns or in selected columns on a sheet, at the will of the operator, without interfering in any manner with the tabulating action brought about by marginal, or intermediate stops such as have heretofore been used on the tabulating bar or may hereafter be desired to be used.

I am aware that it is possible to modify the construction hereinafter set forth, without departing from the essential principle thereof but as the embodiment described and shown in the drawings has been found in practice to successfully carry out the objects of the invention, illustration thereof is given.

In the accompanying drawings:

Figure 1, is a perspective view showing the invention in use on the tabulating bar of the Ellis machine, together with manually operated tabulating mechanism;

Fig. 2, is a detail view looking toward the front of the tabulating bar and the selective multiple stop, two of the stops being shown in dotted lines in depressed position, and one in full lines in depressed position;

Fig. 3, is a plan view thereof;

Fig. 4, is a detail section on the line 4—4, Fig. 3, the stop being in raised position;

Fig. 4^a is a similar view, the stop being set;

Fig. 5, is a section of the line 5—5, Fig. 3;

Fig. 6, is a bottom view;

Fig. 7, is a rear elevation; and

Fig. 8, is a front elevation of the multiple stop unit by itself, the latch and the catches being removed.

Referring first to Fig. 1, the frame of the machine is shown in dotted lines at 1 and the carriage appears at 2.

The toothed tabulating bar appears at C91. Any suitable means may be used for securing the bar C91 to the carriage 2, said carriage being drawn in the direction indicated by the arrow, Fig. 1, by any suitable spring tension means.

My invention is not restricted to use in connection with any particular calculating machine nor to any particular manually operated tabulating mechanism but it has been successfully used on an Ellis calculating machine and the general outline of the frame 1 and carriage 2, Fig. 1, is intended to represent that machine.

It will be understood that the carriage 2 is intended to travel in the direction represented by the arrow and to be arrested in an tabulating position. For the purpose 5 of releasing the carriage so that it may move from one tabulating position to another so that printing may occur in the desired column, there is illustrated in Fig. 1 a depressible tabulating key K60 which is normally 10 held in raised position by a spring K72 co-operating with a pawl F56 which, in turn, is for operating a lever F567. The lever F567 is engaged with another lever F50 which is adapted to engage a pin on the 15 plunger F473. The plunger F473 tends to rise by the action of a spring F73 connected to it and to the frame 1. The upper end of the plunger F473 serves as a stop to engage any one of the selective stops of the 20 present invention when said plunger is in the raised position shown in Fig. 1. Said plunger may also engage with any other stop carried by the bar C91 to arrest the carriage 2 in a manner well-known to the Ellis 25 machines and as shown in the aforesaid Ellis patents.

At 61F and F61 are shown tips of levers controlling different actions or functions of the machine as disclosed in the aforesaid 30 Ellis patents.

My attachment, now to be described has on its body one or more ribs or projections adapted to engage with the tips F61 and 61F to control the desired functions of the machine as will presently appear.

The plunger F473 and the parts 61F, F61 operate through slots in a plate 3 suitably secured to the frame 1 below bar C91.

My present improvements embody a plurality of tabulating stops carried by a body 40 and adapted to be latched in depressed or set position by a latch or shutter which is common thereto, and catches for holding the body on the bar C91 in any desired position.

The body or carrier appears at 4, being 45 in the form of a slide having a top and front wall and a bottom wall, that is, of channel form in cross section. This carrier is slidably mounted on the bar C91, three sides of which it embraces, and it is adapted to be locked on said bar by spring actuated catches 5 which engage the teeth on the upper side of the bar and are held in engagement there- 50 with by springs 6, coiled around a hinge pin 7 which is mounted in projecting parts 8 of the carrier 4.

The carrier 4 is provided with upright 60 slots 9. A plate 10 extends along the face of the carrier 4 and serves as a cover for the slots 9, said plate being secured to the carrier 4 by screws 11.

The selective stops appear at 12, there being 65 as many of these stops as may be desired and they are spaced apart such dis-

tances that they will represent the desired spacing between different columns on the paper used in the machine or between different desired points for the printing of numbers.

The stops 12 are slidably mounted in the channels or grooves 9 and they are retained in position by the plate 10 as best shown in Fig. 8. The stops are provided with suitable finger pieces at their upper ends so that they may be readily depressed. Spring 13 interposed between the finger pieces of the stops and the top of the carrier 4, elevate the stops when they are free. The ends of the springs 13 may be held by studs 14, 15 carried, respectively, by the stops and the carrier 4.

The stops are provided with pins 16 which have cam faces 17, Fig. 4.

To latch down any stop or stops which may be depressed, I provide a latch or shutter 18 which has ears pivoted on the hinge pin or rod 7. The latch is kept pressed toward the plate 10 by the springs 6, one end of each spring being engaged with the latch as shown at 19.

The cam faces 17 of the pins are arranged to engage the latch 18 and when one of the stops carrying one of these pins is depressed the latch will be pressed outward by the cam until, finally, the pin 16 passes below the lower edge of the latch whereupon the depressed stop will be held down by the engagement of the latch with the pin 16 as shown in Fig. 4^a. The stop will be retained in its set position as shown by full lines, Fig. 2, until the shutter or latch 18 is pressed back by applying the finger to the finger piece 18 thereof or until another one of the stops is depressed.

If a stop has been set and the use of another stop is desired, on depressing the second stop, the latch 18 will be released from the pin 16 of the stop first set whereupon the stop first set will be released and will snap upwardly, the stop last set then being retained by the latch 18 which engages the pin 16 thereof.

Thus, the latch 18 serves as a locking means common to all of the stops and it releases any stop or stops previously set, when another stop is set.

On the other hand, any number, or all of the stops may be latched or depressed at the same time if such stops are simultaneously depressed or are held down by the fingers when depressing one or more additional stops.

While I have shown only three stops, it will be understood that more than three, or only two may be used.

One edge of the stop serves as a shoulder 20 and its other corner is beveled at 21. The edge 20 is adapted to abut the upper end of the plunger F473 to arrest the car-

riage in the position determined by the stop which is set. The beveled edge 21 rides on the plunger F473 and depresses said plunger on the return movement of the carriage, 5 should a stop or stops be set.

The bottom of the body or carrier is provided with a longitudinally extending rib 22 which has beveled ends 23 and is arranged to co-operate with the levers 61F, 10 F61. One or more of these ribs may be used and they may be the same for all stops or may be different at each depressible stop, according to the character of the work to be done.

15 What I claim is:

1. The combination with the movable paper-carrying-carriage of a machine adapted for printing characters, of a selective, multiple, tabulating stop, comprising a body 20 or carrier mounted on said paper-carriage, a plurality of independently settable stops carried by said carrier, a latch common to said plurality of stops which locks any stop that is set and releases any previously set 25 stop, and projections from said body which are independent of the stops and are adapted to control the functions or different actions of the machine on which the multiple stop is used.

30 2. The combination with the movable carriage of a machine adapted for printing characters, said carriage being adapted to carry a rotatable paper-holding-platen, of a carrier, independent selectively settable 35 stops unitary with the carrier, said carrier and stops being mounted on, and shiftable with said movable carriage, and latching

means for holding in set position any stop which has been set, said latching means also automatically releasing any previously 40 set stop or stops when another stop is set.

3. The combination with the movable paper-carrying-carriage of a machine adapted for printing characters, of a carrier, independent selectively settable stops unitary 45 with the carrier, said carrier and stops being mounted on, and shiftable with said movable carriage, and also being adapted to be shifted as a unit to different locations on said carriage, and latching means for holding in set position any stop which has been set, said latching means also automatically releasing any previously set stop or stops when another stop is set.

4. The combination with the movable paper-carrying carriage of a machine adapted for printing characters, said carriage being adapted to carry a rotatable paper-holding platen, of a tabulating bar carried by said carriage, a bodily shiftable carrier adapted to be located at different points of the length of said tabulating bar and to move therewith, independent selectively settable stops unitary with the carrier, and latching means for holding in set position 55 any stop which has been set, said latching means also automatically releasing any previously set stop or stops when another stop is set, said carrier and stops being adapted 60 to be shifted as a unit to different positions 65 of the length of said tabulating bar.

In testimony whereof I affix my signature.

EMIL JOHN ENS.
